ROLL PAPER HOLDER

Filed June 18, 1923

Fig 1

UNITED STATES PATENT OFFICE.

JAMES D. CHEESMAN, OF KANSAS CITY, MISSOURI.

ROLL-PAPER HOLDER.

Application filed June 18, 1923. Serial No. 645,965.

To all whom it may concern:

Be it known that I, JAMES D. CHEESMAN, a citizen of the United States, residing at Kansas City, in the county of Jackson and State of Missouri, have invented a certain new and useful Improvement in Roll-Paper Holders, of which the following is a specification.

My invention relates to improvements in roll paper holders.

It is particularly well adapted for use in connection with paper rolls, each having an axial hole adapted to receive in its ends conical supporting blocks carried on a supporting shaft, such as rolls of waxed paper used for wrapping bread.

One of the objects of my invention is to provide a holder of the kind described which is simple, cheap to make, durable, not liable to get out of order, which can be easily and quickly adjusted to fit paper rolls of different widths and with which the paper roll can be quickly bodily adjusted endwise and readily mounted in or removed from the place where it is to be used.

The novel features of my invention are hereinafter fully described and claimed.

In the accompanying drawing, which illustrates the preferred embodiment of my invention,

Fig. 1 is an elevation of my improved roll paper holder and a paper roll mounted thereon and shown in longitudinal section.

Fig. 2 is a side elevation of what is shown in Fig. 1.

Fig. 3 is a sectional view on the line 3--3 of Fig. 2.

Fig. 4 is a sectional view on the line 4--4 of Fig. 1.

Fig. 5 is an enlarged sectional view on the line 5--5 of Fig. 2.

Similar reference characters designate similar parts in the different views.

1 designates the two side members of the frame of a bread wrapping machine to which are respectively secured two rearwardly extending bearing plates 2, each of which is provided in its upper edge with a U-shaped notch 3, Figs. 2 and 3. 4 designates a transverse rotary shaft, which has longitudinally adjustable thereon a member, preferably a sleeve 5, which at its outer end is provided with an annular peripheral groove, 6, Figs. 3 and 4. The adjacent end of the shaft 4 is threaded and has fitted thereon a nut 7 adapted to bear against the adjacent

end of the sleeve 5 for forcing the latter inwardly on the shaft 4. The shaft 4 and sleeve 5 are respectively rotatably mounted and longitudinally slidable in the notches 3 of the plates 2, which provide supporting means for the shaft and sleeve which can be readily placed in or lifted out of the notches.

Two roll supporting devices, preferably two conical blocks 8 are respectively longitudinally adjustable on the shaft 4 and sleeve 5 to which they may be rigidly secured by set screws 9, and the inner tapering surfaces of which are adapted to be respectively fitted in opposite ends of a paper roll 10 through which the shaft 4 extends.

Approximate adjustment of the blocks 8 may be had by moving them endwise on the shaft 4 and sleeve 5, following which, they may be tightened against the paper roll by adjusting the nut 7. For bodily moving the shaft 4 and sleeve 5 endwise to adjust the paper roll 10 endwise, suitable means is provided comprising preferably an upright lever 11, the lower end portion of which is pivoted by a pin 12, disposed horizontally at right angles to the shaft 4 and mounted in a bracket 13, which is secured to the outer side of the adjacent frame member 1.

The upper end of the lever 11 is bifurcated, the arms thereof having respectively fitted in them two screws 14, the inner ends of which are disposed in the groove 6 of the sleeve 5 at diametrically opposite sides of the sleeve.

For oscillating the lever 11, to move the shaft 4 and sleeve 5, longitudinally in opposite directions, to obtain a required adjustment of the paper roll 10, the lever 11 has provided in it a hole 15, in which is mounted a block 16, Figs. 4 and 5, which at its ends is pivotally supported on two screws 17, mounted in the lever 11, at opposite ends of the hole 15.

The block 16 has extending through it a threaded hole in which is fitted a screw 18 having at its inner end a reduced threaded portion which extends through and is rotatable in an arm 19 which extends upwardly from the bracket 13. The inner end of the screw 18 has fitted on it a nut 20, adapted to bear against the inner side of the arm 19.

By turning the screw 18 alternately in opposite directions, the lever 11 may be oscillated to shift the sleeve 5, shaft 4 and paper

roll 10 endwise in opposite directions, for properly positioning the paper roll.

In the operation of the invention, the nut 7 and sleeve 5 are removed from the shaft 4. 5 The paper roll 10 is then slipped onto the shaft, after which the sleeve 5 is slipped onto the shaft with the blocks 8 mounted in the ends of the paper roll and held tightly therein by screwing the nut 7 tightly against the sleeve 5. The latter and the shaft 4 are then mounted in the notches 3 of the plates 2, with the screws 14 disposed in the annular groove 6. The screw 18 is then turned so as to swing the lever 11 in a manner such that the paper roll 10 will be adjusted to its proper operative position.

When the paper roll has been all unwound from the blocks 8, the sleeve 5 and shaft 4 may be lifted out of their bearings and a new roll mounted in the place of the one that has been used in the manner already described.

I do not limit my invention to the structure shown and described, as many modifications, within the scope of the appended claims, may be made without departing from the spirit of my invention.

What I claim is:—

30 1. In a roll paper holder, a rotary shaft, supporting means therefor, a member longitudinally adjustable on the shaft, two devices respectively secured to and rotatable with said shaft and said member and adapted to respectively engage and support the ends of a paper roll, means for adjusting one of said members toward and from each other, and means for simultaneously adjusting said member and said shaft longitudinally, substantially as set forth.

45 2. In a roll paper holder, a rotary shaft, supporting means therefor, a sleeve longitudinally adjustable on said shaft, two devices secured respectively to and rotatable with said shaft and sleeve, means for adjusting the sleeve longitudinally, and means for simultaneously moving the sleeve and shaft longitudinally in either direction, substantially as set forth.

50 3. In a roll paper holder, a rotary shaft, supporting means therefor, a member longitudinally adjustable on said shaft, two devices respectively secured to and rotatable with said member and said shaft adapted to respectively engage and support opposite ends of a paper roll, means for adjusting said member longitudinally on said shaft,

a lever engaging said member, and arranged when oscillated to move said member longitudinally in opposite directions, and means 60 by which said lever may be oscillated, substantially as set forth.

4. In a roll paper holder, a rotary shaft having a threaded portion, a nut fitted on said threaded portion, a sleeve longitudinally movable on said shaft and engaging and adapted to be moved in one direction by said nut, two devices respectively secured to and rotatable with said shaft and said sleeve and adapted to respectively engage 70 and support opposite ends of a paper roll, means for adjusting said sleeve longitudinally in opposite directions, and supporting means on which said shaft and sleeve are rotatable and longitudinally slid able, substantially as set forth.

5. In a roll paper holder, a rotary shaft having a threaded portion, a nut fitted on said threaded portion, a sleeve longitudinally movable on said shaft and bearing 80 against said nut and provided with a peripheral groove, two devices respectively secured to and rotatable with said shaft and sleeve and adapted to respectively engage and support opposite ends of a paper roll, supporting means on which said shaft and sleeve are rotatable and longitudinally slid able, a lever engaging said sleeve in said groove and arranged when oscillated to move the latter longitudinally in opposite directions, and means including a screw for oscillating said lever, substantially as set forth.

6. In a roll paper holder, a rotary shaft having a threaded portion, a nut on said threaded portion, a sleeve longitudinally 95 adjustable on said shaft and having an annular peripheral groove, two devices respectively secured to and rotatable with said shaft and sleeve, supporting means on which said shaft and sleeve are rotatable and longitudinally slid able, a lever pivoted to said supporting means and engaging said sleeve in said groove and arranged when oscillated to move said sleeve endwise in opposite directions, a block pivoted to said lever and having a threaded hole at right angles to the axis of said lever, and a screw fitted in said hole and rotatable in and held from endwise movement by said supporting means, substantially as set forth.

In testimony whereof I have signed my name to this specification.

JAMES D. CHEESMAN.
